CHANGEABLE LIGHTING DEVICE FOR GAMES

Howard F. Maurer, North Tonawanda, N. Y.

Application October 8, 1940, Serial No. 360,277

6 Claims. (Cl. 273—118)

This invention relates generally to amusement apparatus but more particularly to certain new and useful improvements in lighting effects therefor.

One of its objects is to provide a changeable lighting unit for game boards which is so designed as to be operatively-controlled from movable elements employed for playing the game.

Another object of the invention is to provide an impact-controlled lighting unit or assembly which is so constructed that for each impact of the movable element of the game board thereagainst an effective and distinctive color-change of lighting is produced.

A further object is to provide a color-change lighting unit of this character, which is simple and inexpensive in construction, which is positive and reliable in operation, and which is adaptable for ready installation on game boards.

In the accompanying drawing:

Figure 1 is a perspective view of an amusement apparatus showing my changeable lighting units associated therewith. Figure 2 is an enlarged vertical section of one of the lighting units taken substantially on line 2—2, Figure 1. Figures 3, 4 and 5 are horizontal sections taken on the correspondingly numbered lines in Figure 2. Figure 6 is a detached perspective view of the impact-governed, switch control members for effecting the sequence-changing of the light or lights included in the circuit therewith. Figure 7 is a diagram of the electric circuit of one of the lighting units.

Similar characters of reference indicate corresponding parts throughout the several views.

By way of example, I have shown my changeable lighting unit in connection with an amusement apparatus having a playing board 10 on which a plurality of suitably spaced illuminable bumpers 11 or like elements are mounted and against which balls or like objects are adapted to be projected for governing the illumination thereof and more particularly for initiating a change of color of such illumination at each successive impact of a ball against such bumpers.

Each of these bumpers or ball impact elements may consist of a substantially cylindrical transparent member 12 rising from the game board in register with an opening 13 therein and adapted to be illuminated by an electric lamp 14 in line with such openings and mounted on a bracket 15 secured to the underside of the board. Operatively associated with the bumper and included in the circuit of this lamp is a normally open switch adapted to be momentarily closed by im-

pact whenever a ball strikes the bumper, such switch preferably including a yieldable element 16 suspended from and disposed in spaced relation about the bumper member 12, as shown in Figure 2, and adapted to be projected against a fixed switch element 17 applied to such bumper for momentarily closing the circuit thereof to illuminate the bumper. Referring to the electrical diagram shown in Figure 7, the numeral 18 indicates a source of power having one of its terminals connected by a wire 19 with the movable switch element 16 while the other terminal thereof is connected by a wire 20 with the fixed switch element 17, the lamp 14 being connected in series therewith.

Disposed in operative relation with each illuminable member 12 and its lamp 14, is a means for effecting an intermittent color change of such illuminable member in response to each consecutive impact closing of the switch 16, 17. By preference, this means consists of a color screen in the form of a rotatable disk 21 having a plurality of color panels or plates 22 thereon, this disk being interposed for movement between the illuminable element and its companion lamp, whereby the rays of light from the latter will be transmitted through one or another of the color plates in register therewith to correspondingly illuminate the member 12 a like color. This disk 21 is adapted to be rotated a fraction of a revolution in response to each impact closing of the switch and is fixed to one end of an operating shaft 23 journaled in suitable bearings applied to a bracket 24 depending from the game board 10, the other end of said shaft having a toothed wheel 25 thereon which is adapted to be actuated electrically a fraction of a revolution at each closing of the switch 16, 17. For this purpose, there is included in the circuit of this switch, a solenoid 26 whose coil is series-connected in such circuit and whose armature 27 is provided with a dog or pawl 28 adapted to engage one or another of the teeth of the wheel 25 to advance it a fraction of a revolution each time the solenoid is energized to register one or another of the color panels 22 with the lamp 14. As shown in Figure 5, this feed pawl is slidably mounted on the armature and has a spring 29 connected thereto for constantly urging it into the path of the toothed wheel. By this construction, as a ball is projected over the game board it encounters one or another of the bumpers 11, the companion switch 16, 17 is closed and not only lights the lamp 14 but energizes the solenoid 26 to actuate the color screen 21 and there-

by produce an effective and striking change in color of the illuminable element 12 of the companion bumper.

The numeral 30 indicates a plurality of auxiliary lamps which are operatively associated with the game board and which are adapted to be individually lighted, one at a time, in consecutive fashion for each color change operation made in conjunction with the illuminable bumper. To this end these lamps are connected at one terminal to the wire 19 while their other terminals are connected to corresponding wires 31 leading to companion switches 32 disposed in a row and connection to a common wire 33 leading to the source of current supply 18. Each of the switches 32 is normally open and includes a movable switch element 34 adapted to be moved to a closed position by a companion registering cam 35 applied to the shaft 23. These several cams are disposed at different radial points about the shaft so that at each impact closing of the switch 16, 17, one of the cams is brought into operative engagement with its companion switch element 34 so as to close the switch 32 and light the lamp 30 connected thereto.

A flat spring keeper 36 engages a substantially square-shaped cam 37 applied to the shaft 23 to assist the pawl 28 in turning the shaft a quarter of a revolution.

I claim as my invention:

1. In a device of the character described, a game board over which balls are adapted to roll, an illuminable element mounted thereon and including a yieldable ball-impacting member, a normally open switch including said member as a part thereof and movable to a momentarily closed position by impact of a ball against the same for illuminating said element in response to each impact, a changeable color unit movably disposed in correlation with said illuminable element for varying its color when moved to different positions, and means operatively connected to said color unit and included in the circuit of said switch for actuating such unit from one color display position to another.

2. In a device of the character described, a game board over which balls are adapted to roll, an illuminable element mounted thereon, a normally open switch movable to a momentarily closed position by impact of a ball against the same for illuminating said element in response to each impact, an intermittently-movable color unit disposed in correlation with said illuminable element for varying its color when moved to different positions, and electrically-actuated means governed by said switch and operatively connected to said color unit for actuating it a predetermined distance at each impact closing of the switch.

3. In a device of the character described, a game board over which balls are adapted to roll, an illuminable element mounted thereon, a nor-

mally open switch movable to a momentarily closed position by impact of a ball against the same for illuminating said element in response to each impact, an intermittently rotatable member having a variable color screen thereon for registering relation with said illuminable element and an actuatable part for controlling its intermittent motion, and electrically-actuated means governed by said switch and operatively engageable with said actuatable part for governing the intermittent rotation of said color screen member to different positions at each impact closing of the switch.

4. In a device of the character described, a game board over which balls are adapted to roll, an illuminable element mounted thereon, a normally open switch movable to a momentarily closed position by impact of a ball against the same for illuminating said element in response to each impact, an intermittently rotatable shaft having a color screen thereon for operative registering relation with said illuminable element and a toothed member, and electrically-actuated means governed by said switch and including a dog actuated thereby and operatively engageable with said toothed member at each impact closing of the switch for transmitting motion to said shaft to present its color screen at different positions in relation to the illuminable element.

5. In a device of the character described, a playing board over which balls are adapted to roll, an illuminable element mounted thereon, a variable color means movably associated with said element to assume different positions relative thereto and create different color effects thereon, an electric circuit including a normally open, impact-governed switch disposed in the path of and adapted for actuation by said balls to a momentarily closed position, means operatively connected to said variable color means for intermittently moving it to different color display positions, and means included in said circuit for actuating said intermittently movable means in response to successive impact closings of the switch by the balls.

6. In a game apparatus, a playing board having a plurality of illuminable bumper members rising therefrom and over which balls are adapted to roll for impacting engagement with said members, means associated with each of the bumper members for effecting a color change thereof at each successive impact of a ball against the same, an electric circuit including a normally open, ball-impact governed switch for each bumper member adapted to be momentarily closed upon a ball encountering such member, and means in said circuit and operatively connected to said color change means for actuating the same to change the color of the bumper member at each consecutive closing of said switch by one or another of the balls.

HOWARD F. MAURER.
